TERMINAL-BUSHING WITH MEANS FOR CONTROLLING MAGNETIC HEATING

Herman Kramer, Pittsburgh, Pa., assignor to Westinghouse Electric Corporation, East Pittsburgh, Pa., a corporation of Pennsylvania

Application October 28, 1954, Serial No. 465,220

2 Claims. (Cl. 174—152)

This invention relates to terminal bushings in general, and, more particularly to terminal bushings carrying current of such magnitude as to make magnetic or eddy current heating a problem.

A general object of my invention is to provide an improved terminal-bushing construction in which magnetic heating is effectively controlled, or considerably minimized.

Another object of my invention is to provide an improved terminal-bushing construction suitable for carrying current of considerable magnitude in which suitable provision is made for controlling magnetic heating.

My invention is particularly adapted to terminal bushing structures in which considerable current is carried by the current-carrying stud. Although I show only certain applications in the following specification, it is to be clearly understood that bushings adaptable for use in other equipment such as large generators may incorporate features of my invention.

Further objects and advantages will readily become apparent upon reading the following specification, taken in conjunction with the drawings, in which:

Figure 1 is a side elevational view of a terminal bushing mounted through a tank structure, the latter being shown fragmentarily in vertical section;

Fig. 2 is an enlarged vertical sectional view through the flange assembly for the bushing of Fig. 1;

Fig. 3 is a vertical sectional view through the flange mounting ring of the flange assembly taken along the line III—III of Fig. 4;

Fig. 4 is a plan view of the flange mounting ring of Fig. 3;

Fig. 5 is a graph showing a comparison between temperature rise and current-carrying capacity for various flange structures, to indicate the marked improvement obtained by a utilization of my invention;

Fig. 6 is a vertical sectional view through the upper cap assembly of the terminal bushing of Fig. 1, showing how my invention may be applicable to the spring base of the compression spring assembly enclosed within the terminal cap of the bushing;

Fig. 7 is a plan view of the spring base utilized in the compression spring assembly enclosed within the terminal cap illustrated in Fig. 6;

Fig. 8 is a vertical sectional view taken substantially along the line VIII—VIII of the spring base shown in Fig. 7;

Fig. 9 is a side elevational view of a disconnecting switch structure illustrating a further application of my invention;

Fig. 10 is an enlarged plan view of one of the mounting flanges used in the disconnecting switch structure of Fig. 9;

Fig. 11 is a sectional view taken substantially along the line XI—XI of the flange support of Fig. 10; and

Figs. 12 and 13 are somewhat diagrammatic views indicating the principles pertinent to my invention.

In many applications it is necessary to use a metal tube,

2

disc, or an annular plate as a structural part surrounding an electrical conductor. If such a member is utilized as a structural support, it is necessary that it be made out of a material of the requisite strength. Steel is widely used for structural support members, but since steel is magnetic, the result is that magnetic heating becomes a problem. Consequently, when the current passing through the electrical device is large, or the spacing between the current-carrying terminal stud and the structural support is small, it is necessary to make the disc, tube, or other structural support member of non-magnetic material, unless the magnetic flux within such a member is reduced in some other manner.

On condenser bushings of the high-voltage type, or in bushings of lower voltage rating, which are not of the condenser type, many such structural parts are required and used. For example, on a particular type of 1200 ampere terminal bushing, the flange rim and the spring cap base are made of steel with a non-magnetic weld across the flux path. Development work on 1600 and 2000 ampere terminal bushings has shown that heating in these parts becomes a limitation.

Non-magnetic welds used, as described above, are relatively inexpensive and permit the use of steel flanges through 1200 amperes. The effectiveness varies with the width of the weld and the amount of diffusion of parent metal into the weld. However, even the best weld as used, permits less than 50% increase in current. I propose to accomplish the necessary reduction in magnetic flux density by providing a conducting path that will act as a shorted transformer winding. For example, in a bushing of the type illustrated in Fig. 1, generally designated by the reference numeral 1, and mounted to a tank structure 2, a flange assembly 4, shown more particularly in Figs. 2-4, includes a ring-shaped steel mounting flange 6, shown more particularly in Figs. 3 and 4. This is secured by soldering to the grounded brass supporting tube 7, which encircles the condenser wrappings of the bushing 1. Secured to the upper side of the flange ring 6 is a metallic casing 8 having an upper flange ring 9, against which the upper porcelain casing 10 of the bushing 1 rests.

A lower porcelain casing 11 abuts against a lower flange ring 12 secured to the lower end of the tube 7, and an interiorly disposed terminal conductor stud 13 passes interiorly through the bushing 1, and serves as a tension member to maintain the two porcelain casings 10, 11 in compression against the intermediately disposed flange assembly 4.

As observed in Fig. 1, the tank structure 2 has an upstanding flanged collar 15, to the side of which is secured, as by welding, a mounting ring 16. Mounting bolts 17 and nuts 18 fixedly secure the mounting flange 6 of the flange assembly 4 of the terminal bushing 1 to the upper side of the flanged collar 15 in the manner illustrated in Fig. 1, the mounting bolts 17 being positioned within slots 19 of the mounting flange 6, as illustrated in Fig. 4.

It is desirable to use for the mounting flange 6 a material which is of the requisite structural strength, and steel is preferred for this purpose. However, as well known, steel is magnetic, and hence, when surrounding a current-carrying lead, may be subject to magnetic heating.

Fig. 12 diagrammatically represents the conditions present within the current-carrying stud 13 and the mounting flange 6 according to usual practice. The instantaneous current flow is represented through the stud 13 by the arrows 20. This gives rise to the establishment of magnetic flux within the annularly shaped mounting flange 6 in the direction into the paper indicated by the crosses in Fig. 12. Circulating eddy currents are set up, which tend to oppose this establishment of magnetic flux, such

eddy currents being diagrammatically represented by the curved arrows 21. The direction of these circulating eddy currents is such, of course, by Lenz' Law, in a direction to oppose the establishment of the magnetic field. When the current through the terminal stud 13 is alternating, as is the usual case, the continued establishment, decay, and reversal of magnetic flux within the magnetic mounting flange 6 gives rise to considerable heating caused by the circulating eddy currents 21.

I have run a heating test on a mounting flange of the type designated by the reference numeral 6 in Figs. 3, 4 and 12 for various current values through the current-carrying stud, and curve A in Fig. 5 indicates the marked temperature rise in the flange 6 as a function of increasing amperage passing therethrough. This heating effect is, of course, caused by the circulating eddy currents 21 of Fig. 12, which tends to oppose the magnetic field set up in the mounting flange 6 by the passage of current through the terminal stud 13. It is to overcome this problem that my invention is directed.

Curve B in Fig. 5 shows the improvement resulting from making a V cut completely through one side of the mounting flange 6 and running three passes of nonmagnetic weld into such a V slot. It will be noted that by an interposition of such a nonmagnetic weld the flux intensity is reduced, and consequently the heating effected within the mounting flange 6, as caused by circulating eddy currents, is somewhat reduced.

Curve C in Fig. 5 indicates a somewhat improved condition obtained by cutting a right-angle slot across one side of the mounting flange 6, placing therein a non-magnetic slug, such as copper, and making nine-passes of nonmagnetic weld about the slug to fill up the slot in the mounting flange 6. As shown by curve C this reduces the intensity of the magnetic flux within the mounting flange 6, and consequently reduces the heating effect caused by the circulating eddy currents.

I have discovered that by providing an adherent coating 22 of good conducting material upon the surface of the mounting flange 6 and integral therewith, as indicated in Fig. 3, that the heating effect is drastically reduced, as indicated by the curve D of Fig. 5. The conducting path may be provided by plating the mounting flange 6 with copper, or other low resistance material, and with the plating thickness of approximately 0.050 inch the heating curve D of Fig. 5 was obtained. As shown in Fig. 5, the plated flange had a temperature rise of 13° C. at 2000 amperes compared to 110° C. for a plain flange and 60° C. to 88° C. for flanges with non-magnetic welds, all for the same current. It is, therefore, a purpose of my invention to provide steel or magnetic flanges with a heavy adherent copper or conducting coating, plated or sprayed on, or otherwise integrally placed, so that such magnetic flanges may be used on bushings and on other applications where desired. As illustrated in Fig. 3, the conducting coating 22 completely encompasses a segmental portion of the annular flange 6.

Not only may the mounting flange 6 of the flange assembly 4 in Fig. 2 be provided with the conducting coating 22, but a coating 22 may be utilized in connection with other structural members encircling the current-carrying part.

For example, Fig. 6 shows the upper cap assembly 24 of the terminal bushing of Fig. 1, within which is disposed the compression-spring assembly 25. As well known by those skilled in the art, the compression-spring assembly 25 serves the purpose of placing the conductor stud 13 under tension, while at the same time placing the porcelain casings 10, 11 and the intermediately disposed flange assembly 4 under compression. The upper spring plate 26 abuts against a shoulder 27 disposed on the conductor stud 13, and has a plurality of guide bolts 28 passing therethrough, which are threaded into a lower spring plate 29, as shown in Fig. 6. The spring base 30 is preferably formed of steel and, as shown, to minimize

the effect of circulating eddy currents has the conducting adherent coating 22 provided on its surface.

As shown, a gasket 31 is provided between the porcelain casing 10 and the under surface of the spring base 30. Figs. 7 and 8 more particularly show the configuration of the coated spring base 30. The external casing 32 of the cap assembly 24 may be formed of steel because it is positioned at a relatively great distance away from the interiorly disposed current-carrying conductor stud 13, and hence, is not affected to the extent that the spring base 30 is by the passage of current through the conductor stud 13. By providing the adherent integral conducting coating 22 about the spring base 30 magnetic heating is eliminated or considerably reduced.

Fig. 13 illustrates somewhat diagrammatically the conditions arising in the conductor stud 13 and in the spring base 30 as a result of utilizing the adherent integral conducting coating 22. Assume that the same magnitude of current 29 is passing through the conductor stud 13 in Fig. 13 as was present under the conditions assumed in Fig. 12. Whereas the magnetic flux set up in the mounting flange 6 of Fig. 12 caused circulating eddy currents 21 with their attendant heating effect, in Fig. 13, by the use of the short-circuited loop 22 resulting from the plating, or coating, of the surface of spring base 30, the establishment of an appreciable amount of magnetic flux within the interior of the spring base 30 was presented. The current, represented by the arrows 33 in the adherent coating 22 on the surface of the spring base 30 represents an application of Lenz' law. The short-circuited loop, formed by the plating 22, acts as a flux suppressor, and by the passage of current through the coating prevents any build-up of magnetic flux within the spring base 30. The heating effect is therefore considerably reduced as illustrated by the curve D of Fig. 5 contrasted with the other curves A, B and C there illustrated.

Fig. 9 illustrates still a further application of my invention involving a disconnecting switch structure 35. The terminal pad 36, to which a line connection is made, is integrally formed with a jaw contact 37, the latter being supported by a ceramic post 38 upon a channel support or base 39. A disconnecting switch blade 40 is pivotally mounted at 41 to one end of a conductor stud 42, which passes interiorly through a porcelain cylinder 43 and terminates at the terminal pad 44. The porcelain or ceramic cylinder 43 is supported by a mounting flange 45, more particularly shown in Figs. 10 and 11, and preferably made of cast iron. To prevent the effect of magnetic heating, the mounting flange 45 is sprayed, or plated, with an adherent conducting coating 22 to form a short-circuited conducting loop about the sides of the flange 45. The coating 22 prevents or suppresses the build-up of magnetic flux within the interior of the mounting flange 45 in the manner illustrated in Fig. 13 of the drawings.

From the foregoing description of several embodiments of my invention, it will be apparent that it may be used in connection with any magnetic structural member utilized in conjunction with a current-carrying lead. The invention may be utilized in connection not only with bushings of the type shown in Figs. 1 and 9, but also with other types of bushings for carrying current, such as bushings associated with generators, transformers or any type of rotating equipment. Wherever a current-carrying stud passes through a support member adjacent thereto composed of magnetic material, by an application of an adherent integral conducting coating, either plated or sprayed upon the surface of the structural member, the establishment of the magnetic flux therein is suppressed. Many applications utilizing the principles of my invention will readily suggest themselves to those skilled in the art.

Although I have shown and described specific structures it is to be clearly understood that the same were

merely for the purpose of illustration, and that changes and modification may readily be made therein by those skilled in the art, without departing from the spirit and scope of the invention.

I claim as my invention:

1. A terminal bushing including an axially disposed current-carrying terminal stud for carrying relatively high-amperage alternating currents during operation of the terminal bushing, the terminal bushing having at least one hollow insulating casing surrounding said axially disposed terminal stud and a mounting-flange assembly for supporting the bushing, the mounting flange assembly including a grounded metallic support tube and an annular metallic mounting flange composed of magnetic material and fixed adjacent one end of said metallic support tube, and a thin, adherent, conducting coating covering substantially the entire surface area on all sides of said metallic mounting flange including the inner side thereof, and said thin adherent conducting coating forming a short-circuited loop to suppress the build-up of magnetic flux within the metallic mounting flange during operation of the terminal bushing.

2. A terminal bushing including an axially disposed current-carrying terminal stud for carrying relatively high-amperage alternating currents during operation of the terminal bushing, the terminal bushing having a pair of hollow insulating casings surrounding said axially disposed terminal stud and an intermediately disposed

mounting-flange assembly, the mounting-flange assembly including a metallic grounded support tube and a ring-shaped steel mounting flange secured adjacent one end of the metallic support tube, a thin, adherent conducting coating covering substantially the entire surface area on all sides of said steel mounting flange including the inner side thereof, and said thin adherent conducting coating forming a short-circuited loop to suppress the build-up of magnetic flux within the steel mounting flange during operation of the terminal bushing.
